ELECTRIC CIRCUIT BREAKER

Hans Thommen, Baden, Switzerland, assignor to
 Aktiengesellschaft Brown Boveri & Cie., Baden,
 Switzerland, a joint-stock company of Switzerland

Application July 30, 1937, Serial No. 156,554
 In Germany July 30, 1936

19 Claims. (Cl. 200—146)

This invention relates in general to circuit breakers, and more particularly to breakers of the fluid blast type in which means are provided for inserting a resistor in the circuit to be opened by the breaker to thereby facilitate interruption of the arc therein.

It is well known to provide circuit breakers with contacts controlling the insertion of a resistor in the circuit to be opened by the breaker to reduce the current intensity in the arc and hence facilitate the interruption thereof. In circuit breakers of the fluid blast type, and particularly in circuit breakers of the gas blast type, it has been found that the size of the resistor may be considerably reduced and that the action of the gas blast in extinguishing the arc may be considerably improved by substituting an arrangement of coaxial contacts formed as solids of revolution in place of the usual rectangular contacts, and by utilizing a radial blast rather than a lateral blast for blowing out the arc. As an intermediate step in the operation of the breaker, the fluid blast causes transfer of the arc established between the arcing contacts from one of such contacts to an auxiliary contact coaxial therewith to introduce the resistor into the circuit. The fluid blast may also serve to dissipate the heat evolved in the resistor and the resistor may accordingly be placed in a discharge passage from the arcing chamber.

It is, therefore, one of the objects of the present invention to provide a circuit breaker of the fluid blast type in which a blast of fluid under pressure is utilized to transfer an arc from an arcing contact to an auxiliary contact for inserting a resistor in the circuit controlled by the breaker.

Another object of the present invention is to provide a circuit breaker of the fluid blast type in which an arc is transferred from one contact to another contact coaxial therewith by means of a radial blast of fluid.

Another object of the present invention is to provide a circuit breaker of the fluid blast type in which a blast of fluid having served to transfer an arc to a contact inserting a resistor in the circuit of the breaker is utilized for cooling the resistor.

Objects and advantages other than those above described will be apparent from the following description when read in connection with the accompanying drawing, in which:

Fig. 1 is a view, in side elevation, of a circuit breaker embodying the features of the present invention;

Fig. 2 is a vertical cross section through the arc-

ing chamber of the circuit breaker illustrated in Fig. 1 taken on a plane parallel to the plane of projection utilized in Fig. 1;

Fig. 3 is a vertical cross section through a modified embodiment of the arcing chamber of the circuit breaker differing from the embodiment illustrated in Fig. 2 in the use of a fixed hollow auxiliary contact forming a discharge passage for the arcing chamber; and

Fig. 4 is a vertical cross section through a further modified embodiment of the arcing chamber differing from the embodiment illustrated in Fig. 3 in the use of a movable auxiliary contact.

Referring more particularly to the drawing by characters of reference, Fig. 1 illustrates a circuit breaker comprising as a constructive element thereof a reservoir 6 containing fluid under pressure. Such fluid may be compressed air or any other suitable insulating fluid, but steam may also be used under certain operating conditions.

Reservoir 6 may be connected with the arcing chamber 7 of the circuit breaker through a hollow insulator 8 and through a suitable valve (not shown) which may be controlled by an overload relay 9 mounted on a projection 10 of the wall of chamber 7 forming one terminal of the breaker. Reservoir 6 also supports an insulator 11 on which is mounted the pivot for the movable blade 12 of a disconnecting switch cooperating with the arcing contacts of the circuit breaker as will appear hereinafter.

Switch blade 12 may be actuated by any suitable mechanism such as a compressed fluid motor 13 of the reciprocating type connected therewith through a pair of connecting rods 14, a T-shaped crank 16 and a connecting rod 15 of insulating material. It will be understood that the elements of the circuit breaker may be duplicated and provided in suitable number when the breaker is to be used for controlling the flow of current through a plurality of conductors.

As shown in detail in Fig. 2, chamber 7 is of cylindrical form having a wall preferably made of conductive material provided with a circular port or orifice 17 coaxial with the bore of the chamber.

The lip of the wall of chamber 7 about orifice 17 may be provided with a flange to form an annular fixed contact 18 but it is generally preferred instead to arrange about the orifice a replaceable annular contact of suitable refractory conductive material such as tungsten. A tubular movable contact 19 is supported within chamber 7 and coaxially therewith by means of a piston 21 arranged for reciprocating movement within a

cylinder 22. Cylinder 22 is insulated from the wall of chamber 7 by a lining 23 which thus insulates contact 19 from contact 18 when such contacts are separated. Although contact 19 may be made in one piece it is generally preferred to provide such contact with a renewable arcing portion 24 adapted to engage contact 18 in abutting relation therewith and with another renewable arcing portion 26 to which the arc is to be transferred by a blast of fluid under pressure. Contact portions 24 and 26 may also be made of refractory conductive material such as tungsten.

Contact 19 is generally maintained in abutting engagement with contact 18 by suitable resilient means such as a spring 27 acting between contact 18 and a diaphragm 28 closing the upper end of cylinder 22. Diaphragm 28 is provided with apertures for admitting fluid under pressure from chamber 7 into cylinder 22 to actuate piston 21 and contact 29 and thus separate contacts 19 and 18. The stroke of contact 19 is limited by abutment of the enlarged portion thereof against a cylinder 25 mounted on diaphragm 28 and also serving as guide for contact 19. Piston 21 is provided with suitable projections on which are fastened a pair of resilient contacts 29 adapted to engage switch blade 12 to form a disconnecting switch serially connected with arcing contacts 18 and 19. Piston 30 21 is also provided with an aperture arranged in alignment with the bore of contact 19 to form with such bore an auxiliary discharge passage for chamber 7.

Chamber 7 is provided with an inlet 31 through which fluid under pressure may be introduced to cause operation of piston 21. Chamber 7 is also provided with a main discharge passage 32 communicating with the chamber through orifice 17, and the flow of fluid from chamber 7 into passage 32 may be given a whirling movement by means of helical vanes 33 arranged within the portion of chamber 7 adjacent contact 18. Passage 32 may be of cylindrical shape arranged to form an extension of chamber 7 and serves to confine the fluid blast projected from chamber 7 through orifice 17 upon separation of contacts 18 and 19. Passage 32 is preferably provided with a suitable structure for deionizing and cooling the fluid issuing from chamber 7, for separating therefrom metallic particles detached by the arc from the arcing contacts and for muffling the report produced by the fluid blast. Such structure may consist of a sheet metal baffle 34 wound to form a spiral convolute surface defining a spiral path issuing from passage 32 along a generatrix line of the wall thereof.

An auxiliary contact 36 is arranged outside of chamber 7 within passage 32 and extends into orifice 17 axially thereof. Contact 36 preferably protrudes into chamber 7 to an extent such that when contact 19 is removed from the position shown to the fully open position at a predetermined distance from contact 18, portion 26 of contact 19 is brought to a lesser distance from contact 36. Contact 36 is supported in position by a resistor 37 arranged outside of chamber 7 in passage 32 and fastened to the upper part of the wall of passage 32 in any suitable known manner such as by clamping. Contact 36 is connected through resistor 37 with one of the arcing contacts of the circuit breaker. In the embodiment illustrated in Fig. 2 such connection comprises the conductive wall of passage 32 and the wall of chamber 7, whereby contact 36 is connected with contact 18.

Resistor 37 may be made of any suitable known material such as silicon carbide and is chosen of the proper size to obtain the desired amount of resistance and to form a structure capable of carrying the required amount of current without undue heating. Resistor 37 is insulated from the space within passage 32 by means of a suitable insulation jacket 38.

The circuit breaker is inserted in the circuit to be controlled thereby by connecting one terminal of the circuit to the support of blade 12 and connecting the other terminal of the circuit with terminal 10 either directly or through a relay 9. When the circuit breaker is closed, the elements thereof are in the position shown in Figs. 1 and 2. When the circuit is to be opened by operation of the circuit breaker, a connection is established between reservoir 6 and insulator 8 either manually or by the action of relay 9 to admit fluid under pressure from reservoir 6 into insulator 8 and chamber 7. Orifice 17 then being closed by contacts 18 and 19, the pressure of the fluid within chamber 7 and within cylinder 22 rises to a value sufficient to cause downward movement of piston 21. Piston 21 separates contact 19 from contact 18 and brings contact 19 into abutting engagement with the upper end of guide 25, and such operation causes an arc to be established between contact 18 and portion 24 of contact 19.

The connection between reservoir 6 and chamber 7 is maintained for a sufficient length of time to cause projection of a blast of fluid under pressure from chamber 7 through orifice 17 into passage 32 and between the convolutions of baffle 34 to the ambient atmosphere while another fluid blast is projected through the bore of hollow contact 19. When vanes 33 are provided, such vanes impart a whirling motion to such fluid blasts. The two fluid blasts jointly occupy the annular space contained between contacts 18, 19 and 36 wherein the fluid flows in a generally radial direction. The arc established between contacts 18 and 19 is thereby urged radially inward towards contacts 26 and 36, and the voltage drop in the arc is caused to increase by the lengthening thereof and by the deionizing effect of the fluid blast. On the contrary, the gap between contacts 26 and 36, which is filled with fluid in a highly ionized condition, requires a gradually decreasing voltage for the establishment of an arc therein by dielectric breakdown.

When such voltage becomes lower than the voltage drop in the arc established between contacts 18 and 19, the arc is transferred from contact 18 to contact 36. It will be understood, however, that when the circuit breaker is connected in an alternating current circuit, such transfer of the arc may take place during the first half cycle of arcing or else an apparent transfer of the arc may be effected by extinction of the arc between contacts 18 and 19 during passage of the arc current through zero and subsequent ignition of another arc between contacts 26 and 36 at the beginning of the following half cycle.

After such transfer the flow of current through the circuit breaker takes place from terminal 10 through the wall of passage 32, resistor 37, contact 36, contact 26, 24, 19, contact 29, and switch blade 12 to the other terminal of the circuit breaker. Resistor 37 causes the arc current flowing between contacts 26 and 36 to have a much lower value than the current previously flowing between contacts 18 and 19 with the result that

the arc is readily extinguished by the blast of fluid projected from chamber 7 through the bore of contact 19. It will be understood that the blast projected through contact 19 is of relatively low intensity compared to the blast projected through passage 32 and that therefore the fluid ionized and heated by the arc established between contacts 26 and 36, issues from contact 19 in a relatively cold and deionized condition. Such blast will accordingly not cause arcing over from contact 29 and switch blade 12 to chamber 7 or to other adjacent conductive members.

The insertion of the resistor in the circuit causes the latter to assume a generally resistive character with the result that any oscillation tending to be established therein by the exchange of energy between the inductive and capacitive portions thereof are damped, and hence the recovery voltage impressed across the contacts is limited to the voltage generated at the source supplying the circuit. In addition to the above actions, the space about contacts 18, 19 and 36 is swept by a blast of cold fluid in an un-ionized condition so that establishment of another arc between the contacts is prevented. Such fluid blast also serves to dissipate the heat produced in resistor 37 by the flow of current therethrough. After extinction of the arc, switch blade 12 may be disengaged from contact 29 by operation of motor 13 to insert, in the circuit, a gap of sufficient length to permanently maintain the circuit open. The supply of fluid from reservoir 6 to chamber 7 may then be discontinued and contact 19 is returned to the position shown under the action of spring 27.

In the embodiment illustrated in Fig. 3, contact 36 is replaced by a tubular contact 39 mounted on a hollow resistor 41. The circuit breaker may then be provided with a solid movable contact 42 instead of hollow contact 19. Contact 42 may, however, be provided with a hollow arcing portion 43 whereto contact 39 may penetrate when contact 42 is in the closed position. In the present embodiment, when fluid under pressure is introduced into chamber 7 a part of the fluid blast projected through orifice 17 upon separation of contacts 18 and 42 is diverted through contact 39 and resistor 41 for causing transfer of the arc from contact 18 to contact 39. The operation of the present embodiment is otherwise identical to that of the embodiment illustrated in Fig. 2.

In the embodiment illustrated in Fig. 4, the fixed auxiliary contact is replaced by a movable tubular auxiliary contact 44 slideable within insulator 38 and within resistor 41. Contact 44 is adapted to engage a solid arcing portion 46 of contact 42 and is urged into engagement therewith by a spring 47. The movement of contact 44 is, however, limited by engagement of a flange 45 thereof with the lower portion of the wall of resistor 41. Spring 47 may be arranged within resistor 41 and maintained in position therein by means of an insulation tube 48. Current is preferably transmitted between contact 44 and resistor 41 by means of a sliding contact 49 clamped on resistor 41.

In the present embodiment, when fluid under pressure is admitted into chamber 7 contact 42 is urged downward as in the embodiment illustrated in Fig. 3. During the first part of the stroke of contact 42, contact 44 is maintained in engagement with arcing portion 46 of contact 42 by spring 47. The flow of current between

chamber 7 and contact 42 is then divided between two parallel paths. Part of such current flows from the wall of chamber 7 through contact 18 and therefrom to contact 42 through the arc established therebetween upon separation 5 thereof. Another portion of such current flows from the wall of chamber 7 through the wall of passage 32, resistor 41, contact 49, contact 44, and contact portion 46 to the body of contact 42. When contact 42 reaches a predetermined position, flange 45 engages the bottom of the wall of resistor 41 and causes contact 44 to stop. Contacts 44 and 42 accordingly separate and the arc established between contacts 18 and 42 is transferred by the fluid blast from contact 18 to contact 44 which is in close proximity to arcing portion 46 of contact 42. The operation of the present embodiment is otherwise identical to that of the embodiment illustrated in Fig. 3.

Although but a few embodiments of the present invention have been illustrated and described, it will be apparent to those skilled in the art that various changes and modifications may be made therein without departing from the spirit of the invention or from the scope of the appended 20 25 claims.

It is claimed and desired to secure by Letters Patent:

1. An electric circuit breaker comprising an arcing chamber having an orifice, an annular 30 fixed contact arranged about said orifice, an auxiliary contact arranged outside of said chamber and extending into said orifice, a resistor arranged outside of said chamber and connecting said fixed contact with said auxiliary contact, a movable contact arranged within said chamber, and means for actuating said movable contact.

2. An electric circuit breaker comprising an arcing chamber having an orifice, a discharge 40 passage for said chamber communicating therewith through said orifice, an annular fixed contact arranged about said orifice, an auxiliary contact arranged within said passage, a movable contact arranged within said chamber, a resistor arranged outside of said chamber and connecting said auxiliary contact with another one of said contacts, and means for actuating said movable contact.

3. An electric circuit breaker comprising an 50 arcing chamber having an orifice, a discharge passage for said chamber communicating therewith through said orifice, an annular fixed contact arranged about said orifice, an auxiliary contact arranged within said passage, a movable 55 contact arranged within said chamber, a resistor arranged outside of said chamber and connecting said auxiliary contact with another one of said contacts, means for actuating said movable contact, and means for projecting a blast of 60 fluid under pressure from said chamber through said orifice upon separation of said fixed and movable contacts.

4. An electric circuit breaker comprising an arcing chamber having an orifice, a discharge 65 passage for said chamber communicating therewith through said orifice, an annular fixed contact arranged about said orifice, an auxiliary contact arranged within said passage, a movable contact arranged within said chamber, a resistor 70 arranged outside of said chamber and connecting said auxiliary contact with another one of said contacts, means for actuating said movable contact, means for projecting a blast of fluid under pressure from said chamber through said orifice 75

upon separation of said fixed and movable contacts, and means for imparting a whirling motion to said fluid blast through said orifice.

5. An electric circuit breaker comprising an arcing chamber having an orifice, a discharge passage for said chamber communicating therewith through said orifice, an annular fixed contact arranged about said orifice, an auxiliary contact arranged within said passage, a movable contact arranged within said chamber, one of said auxiliary and movable contacts being hollow and forming a second discharge passage for said chamber, a resistor arranged outside of said chamber and connecting said auxiliary contact with one of said fixed and movable contacts, means for actuating said movable contact, and means for projecting a blast of fluid under pressure from said chamber through said passages upon separation of said fixed and movable contacts.

6. An electric circuit breaker comprising an arcing chamber having an orifice, a discharge passage for said chamber communicating therewith through said orifice, an annular fixed contact arranged about said orifice, an auxiliary contact arranged within said passage, a movable contact arranged within said chamber, a resistor arranged outside of said chamber and connecting said auxiliary contact with another one of said contacts, means for separating said fixed and movable contacts to thereby establish an arc therebetween, and means for projecting a blast of fluid under pressure from said chamber through said orifice upon separation of said fixed and movable contacts to transfer the arc established therebetween from said fixed contact to said auxiliary contact.

7. An electric circuit breaker comprising an arcing chamber having an orifice, an annular fixed contact arranged about said orifice, an auxiliary contact arranged outside of said chamber and extending into said orifice, a resistor arranged outside of said chamber and connecting said fixed contact with said auxiliary contact, a movable contact arranged within said chamber, means for actuating said movable contact, and means for projecting a blast of fluid under pressure from said chamber through said orifice upon separation of said fixed and movable contacts.

50 8. An electric circuit breaker comprising an arcing chamber having an orifice, an annular fixed contact arranged about said orifice, an auxiliary contact arranged outside of said chamber and extending into said orifice, a resistor arranged outside of said chamber and connecting said fixed contact with said auxiliary contact, a movable contact arranged within said chamber, one of said auxiliary and movable contacts being hollow, means for separating said fixed and movable contacts, and means for projecting a blast of fluid under pressure from said chamber through said orifice and through said hollow contact upon separation of said fixed and movable contacts.

65 9. An electric circuit breaker comprising an arcing chamber having an orifice, an annular fixed contact arranged about said orifice, an auxiliary contact arranged outside of said chamber and extending into said orifice, a resistor arranged outside of said chamber and connecting said fixed contact with said auxiliary contact, a movable contact arranged within said chamber, means for separating said fixed and movable contacts to thereby establish an arc therebetween, and means for projecting a blast of fluid under

pressure from said chamber through said orifice upon separation of said fixed and movable contacts to transfer the arc established therebetween from said fixed contact to said auxiliary contact.

10. An electric circuit breaker comprising an arcing chamber having an orifice, an annular fixed contact arranged about said orifice, an auxiliary contact arranged outside of said chamber and extending into said orifice, a resistor arranged outside of said chamber and connecting said fixed contact with said auxiliary contact, a movable contact arranged within said chamber in contacting engagement with said fixed contact, means for actuating said movable contact whereby said movable contact is removed to a predetermined distance from said fixed contact and to a lesser distance from said auxiliary contact, and means for projecting a blast of fluid under pressure from said chamber through said orifice upon separation of said fixed and movable contacts to transfer the arc established therebetween from said fixed contact to said auxiliary contact.

11. An electric circuit breaker comprising an arcing chamber having an orifice, an annular fixed contact arranged about said orifice, an auxiliary contact arranged outside of said chamber and extending into said orifice, a resistor arranged outside of said chamber and connecting said fixed contact with said auxiliary contact, a tubular movable contact arranged within said chamber, means for separating said fixed and movable contacts, and means for projecting a blast of fluid under pressure from said chamber through said orifice and through said movable contact upon separation of said fixed and movable contacts.

12. An electric circuit breaker comprising an arcing chamber having an orifice, an annular fixed contact arranged about said orifice, a tubular auxiliary contact arranged outside of said chamber and extending into said orifice, a resistor arranged outside of said chamber and connecting said fixed contact with said auxiliary contact, a movable contact arranged within said chamber, means for separating said fixed and movable contacts, and means for projecting a blast of fluid under pressure from said chamber through said orifice and through said auxiliary contact upon separation of said fixed and movable contacts.

13. An electric circuit breaker comprising an arcing chamber having an orifice, an annular fixed contact arranged about said orifice, a movable contact arranged within said chamber in contacting engagement with said fixed contact, an auxiliary contact arranged outside of said chamber and extending into said orifice, a resistor arranged outside of said chamber and connecting said fixed contact with said auxiliary contact, means for urging said auxiliary contact into engagement with said movable contact, means for limiting the movement of said auxiliary contact, means for actuating said movable contact whereby said movable contact is removed to a predetermined distance from said fixed contact and to a lesser distance from said auxiliary contact, and means for projecting a blast of fluid under pressure from said chamber through said orifice upon separation of said fixed and movable contacts to transfer the arc established therebetween from said fixed contact to said auxiliary contact.

14. An electric circuit breaker comprising an arcing chamber having an orifice, a discharge passage for said chamber communicating there-

with through said orifice, an annular fixed contact arranged about said orifice, an auxiliary contact arranged within said passage, a movable contact arranged within said chamber, a resistor arranged within said passage and connecting said auxiliary contact with another one of said contacts, means for actuating said movable contact, and means for projecting a blast of fluid under pressure from said chamber into said passage upon separation of said fixed and movable contacts.

15. An electric circuit breaker comprising an arcing chamber having an orifice, a discharge passage for said chamber communicating therewith through said orifice, an annular fixed contact arranged about said orifice, an auxiliary contact arranged within said passage, a movable contact arranged within said chamber, a resistor arranged within said passage and connecting said auxiliary contact with said fixed contact, means for actuating said movable contact, and means for projecting a blast of fluid under pressure from said chamber into said passage upon separation of said fixed and movable contacts.

20. 16. An electric circuit breaker comprising an arcing chamber having an orifice, an annular fixed contact arranged about said orifice, an auxiliary contact arranged outside of said chamber and extending into said orifice, a resistor arranged outside of said chamber and connecting said fixed contact with said auxiliary contact, a movable contact arranged within said chamber, means operable by fluid under pressure within said chamber for separating said fixed and movable contacts, and means for introducing fluid under pressure into said chamber to cause operation of said contact separating means and to cause fluid under pressure to be projected from said chamber through said orifice.

25. 17. An electric circuit breaker comprising an arcing chamber having an orifice, a discharge passage for said chamber communicating therewith through said orifice, an annular fixed contact arranged about said orifice, an auxiliary contact

tact arranged within said passage, a movable contact arranged within said chamber, a resistor arranged outside of said chamber and connecting said auxiliary contact with another one of said contacts, means operable by fluid under pressure within said chamber for separating said fixed and movable contacts, and means for introducing fluid under pressure into said chamber to cause operation of said contact separating means and to cause fluid under pressure to be projected from said chamber through said orifice.

15. An electric circuit breaker comprising an arcing chamber having an orifice, a discharge passage for said chamber communicating therewith through said orifice, an annular fixed contact arranged about said orifice, an auxiliary contact arranged within said passage, a movable contact arranged within said chamber, a resistor arranged within said passage and connecting said auxiliary contact with another one of said contacts, means operable by fluid under pressure within said chamber for separating said fixed and movable contacts, and means for introducing fluid under pressure into said chamber to cause operation of said contact separating means and to cause fluid under pressure to be projected from said chamber through said orifice.

20. 19. An electric circuit breaker comprising an arcing chamber having an orifice, a discharge passage for said chamber communicating therewith through said orifice, an annular fixed contact arranged about said orifice, an auxiliary contact arranged within said passage, a movable contact arranged within said chamber, a resistor arranged within said passage and connecting said auxiliary contact with said fixed contact, means operable by fluid under pressure within said chamber for separating said fixed and movable contacts, and means for introducing fluid under pressure into said chamber to cause operation of said contact separating means and to cause fluid under pressure to be projected from said chamber through said orifice.

HANS THOMMEN.
